UNITED STATES PATENT OFFICE.

JOHN E. CHATEM, OF LOS ANGELES, CALIFORNIA.

WALL-BED.

No. 890,556.

Specification of Letters Patent.

Patented June 9, 1908.

Application filed November 19, 1906. Serial No. 344,157.

To all whom it may concern:

Be it known that I, JOHN E. CHATEM, a citizen of the United States, residing at Los Angeles, in the county of Los Angeles and State of California, have invented new and useful Improvements in Wall-Beds, of which the following is a specification.

It is the objects of this invention to provide a wall-bed or the like, which can be raised and lowered with perfect ease and without any danger or liability of accidental folding up of the bed, and in which the force exerted for raising and lowering the same will be approximately equal to that required for sustaining the bed throughout the entire movement in either direction; to provide an improved bed-frame adapted to a wall-bed, the same being superior in the matters of strength, rigidity, and lightness combined, so that the force necessary to manipulate the bed may be brought to a minimum; to provide for using such frame either as a wall-bed or as a chamber bed to be moved about the room.

The invention may be carried out in various forms, and I shall illustrate the same in some of the forms in which I contemplate embodying the invention.

The accompanying drawings illustrate the invention.

Figure 1 is a fragmental perspective view of a wall bed embodying my invention, with tension devices of various kinds applied to the same bed-frame. It is to be understood that in ordinary practice, only one kind of tension device would usually be employed in any one bed, although all three devices might be employed if so desired. Fig. 2 is a fragmental plan of the bed shown in Fig. 1. Fig. 3 is a fragmental detail of the bed with the post extensions in place to fit the frame for use for a portable bed. Fig. 4 is a fragmental detail showing the spring tension devices supported against the face of the wall. Fig. 5 is a fragmental, vertical, sectional detail showing the bed in lowered position with the weight tension devices in use, together with spring tension devices. Fig. 6 is a fragmental elevation from line x^y , Fig. 5, looking left. Fig. 7 is a fragmental detail of the coil tension device. Fig. 8 is a fragmental detail of the facing and base, and the hinge which connects the same. Fig. 9 is a detail of one form of clip 6. 1 designates a recessed wall or other body in which the bed is to fold.

2 is a bed-frame.

3 is a facing hinged by hinge 4 to the base 5 of the wall or body 1 to close the wall recess.

The bed frame is preferably constructed of light steel bicycle tubing and fittings, for the purpose of combining great rigidity and extreme lightness. The same will be described more in detail hereinafter. 6 designates clips by which said frame is removably attached to the facing 3, so that the facing and the frame may rise and lower together as the facing is moved on its pivot 4.

7 is a standard or foot which projects from the facing 3 and serves to support the free end of the frame when the bed is in lowered or horizontal position.

Cumulative tension devices are connected with an upright 8 at a point above the pivot 4, and are adapted to exert their force cumulatively to sustain the bed against the force of gravity, as the same is lowered to horizontal position, and to successively cease to exert lifting force on the frame as the same rises to upright position. The tension means for exerting such force may be of different kinds.

In the drawings, springs 9, 10 and 11 take the weight successively in the order named as the bed-frame is lowered, and spring 9 receives the strain of the lowering bed before any such strain comes upon connection 13 which applies tension to spring 10, after which connection 14 acts on spring 11.

In the drawings two sets of like springs are shown. In each set the three springs are connected with a single cross-head 12. The spring 9 being longest, is connected directly to said cross-head; the spring 10 is connected by connection 13, which is of such length as to leave a slack line, as indicated in Fig. 4, after the strain has been applied to spring 9; and spring 11 is connected with a cross-head by connection 14 having more slack than connection 13.

15 is a connection led under a pulley 16 and connecting the cross-head 12 with the bed-frame above the pivot 4 thereof. Said connection 15 may also be connected with the connections 17 which pass over pulleys 18 and are connected with cumulative weights as 19, 20, 21 and 22.

Connections 17 may be in pairs, as shown in Fig. 6, one of said connections being fastened to a weight 19 which in turn is fastened by connections 23 with another weight 21, while the other connection 17' which is con-

connected with connection 15, may be connected with a weight 20 which in turn is connected by connections 24 with weight 22. Connections 17 and 17' are of such length that when the bed-frame is brought to upright position in the recessed body 1, the weights 20, 21 and 22 will all be at rest, the gravity of weight 19 being sufficient to hold the bed in its upright position; or in case 10 weights and springs are used, the combined force of the springs 9 and the weight 19 may be used to serve the purpose of holding the bed in place.

When the frame is lowered the effect will 15 be first to take up the slack of connection 17' until weight 20 is lifted. At the same time the slack of connections 23 will be taken up so that after the weight 20 has been lifted the weight 21 will be acted upon to raise it 20 from its support, as the floor 25. Further downward movement of the bed will take up the slack of the connections 24 until the weight 22 is lifted from its support, as the floor 25.

25 It is evident that the same movement may operate successively upon the springs 9, 10 and 11, the connections of which may be appropriately arranged to bring them successively into action. On return movement of 30 the bed the weights and springs will come to rest in reverse order.

The tension device may be in the form of coil springs, as detailed in Fig. 7, in which spring 26 will be brought into action first on 35 lowering the bed, and spring 27 is of such tension as to come into action later; said springs acting cumulatively after the same manner as that described for the weights and springs 9, 10 and 11.

40 In case it is desired to use the bed apart from the wall and the facing 3, the clips 6 may be loosened and the bed-frame 2 removed from the facing which may then be raised to close the opening 28 in the wall, 45 which opening is normally closed by doors 29 held by springs 30 when the bed is down, the cords 31 serving to draw the doors rearwardly as the bed moves upward. When the frame 2 has been released, the post extensions 32 may be inserted into the sockets 33 in the bed-frame, whereupon said frame becomes an ordinary portable bedstead detached from the wall.

A bed-frame constructed in accordance 55 with this invention, comprises side rails 34 each formed of lower and upper sectional bars 35 and 36, respectively. The sections 37, 38 and 39 are hollow steel tubing connected together by tees 40 and nipples 41, 60 the latter forming uprights to hold the bottom and top bars 35, 36 a distance apart to give rigidity to the frame.

42 designates tees on the corner nipples 41' connected by tubes 43.

65 44 designates tees on nipples or pipe sec-

tions 45, which pipe sections extend upwardly from the corner tees 40'.

46 designates fittings at the tops of the nipples or pipe sections 45, and 47, 48, designate bars held by fittings 44 and 46 to form with the 70 bars 43 the head and foot frames of the bedstead.

49 and 50 designate intermediate cross-bars and rails connected by tees 51 with the side rails of the bed, and by braces 52 with 75 the end bars 47 to which the bed-springs 53 for the mattress will be attached. Braces 54 are provided extending from cross bars 49 at the wall end of the bed to the top rail 48' at such end.

80 55 represents uprights at said wall end of the bed to support the top rail 48'.

All of the parts of the frame are constructed of light steel tubing, and appropriate fittings therefor, and by this construction a 85 superior rigid frame is produced.

The braces 52 and 54 that are connected with the uprights and side-rails of the bed, are set aslant, as shown, to take the strain of the tension devices and of the power ap- 90 plied for pulling the frame down, and also the stress of the springs 53 and their load.

I am not aware that a bed-frame has been heretofore constructed of bicycle tubing. By 95 constructing the frame as shown, the same is made proof against any racking or loosening of parts and will remain rigid and true indefinitely.

The coil springs 26, 27, may have their terminals held by a single clip 56, and may 100 be of different sizes and tensions, as indicated in Fig. 7, so that as the bed swings upward the tension will diminish, and vice versa. In the act of lowering the bed, the strain of the tension devices on the upright 105 8 increases, and such strain continues to be exerted until the bed is again brought to upright position. Provision is made for resisting the strain by constructing the frame of light steel bicycle-tubing with the braces 52 110 and 54.

It is to be understood that in practice, yielding means of determined strength will be employed to sustain the bed including the frame, the mattress, the bed clothing, and all 115 the appurtenances that are to be raised with the bed-frame for storing the same in the recess; and that the strength or power of the successive elements of the cumulative yielding bed-sustaining means will be normally 120 such at each stage of movement as may be required at such stage to cause the process of lowering or raising the bed to require only minimum manual power. By hinging the bed frame to the base board 5 which extends 125 across in front at the lower end of the recess the bed is rigidly held in place in both the upright and the lowered position and the mounting is thus constructed at a minimum cost.

What I claim is:

1. In a bed provided with cumulative tension means, a frame constructed of bicycle tubing and fittings and comprising side rails, 5 each formed of lower and upper sectional bars 35 and 36, respectively, the sections being of hollow steel tubing connected together by T's and nipples, the latter forming uprights to hold the bottom and top bars a distance apart to give rigidity to the frame, cross-bars 43, 47 and 48 held by fittings to form the head and foot frames of the bedstead, intermediate cross-bars and rails 49 and 50 connected by T's with the side rails 10 of the bed and by braces 52 with the end bars 47, to which the bed springs for the mattress may be attached, braces 54 extending from the cross-bars 49 at the wall end of the bed to the top rail at such end, uprights 55 15 at said wall end of the bed to support the top rail, a hinged facing provided with a foot, a recessed wall to which said facing is hinged and resilient means in said recessed wall, flexible means connecting said resilient means 20 with the top rail of the frame, and means de- 25

tachably connecting the frame with the facing.

2. A wall provided with a recess, a bed frame pivoted to fold in the recess, lines fastened to the bed frame above the pivot thereof and led thence under pulleys, said pulleys located at the rear bottom corners of the recess; said lines led thence upwardly, cross-heads above said pulleys, fastened to said lines, and two sets of three springs, the spring 30 of each set being of different lengths, said springs being hung on the back wall of said recess, lines of different lengths connecting the spring of one pair with one of the cross-heads, and like lines connecting the springs 35 of the other set of springs to the other cross-head.

In testimony whereof, I have hereunto set my hand at Los Angeles California this 31st day of October 1906.

JOHN E. CHATEM.
